DESIGN.

J. PELT.

KNITTED CAPE.

APPLICATION FILED FEB. 16, 1922.

61,276.

Patented July 25, 1922.

Inventor,

Joseph Pelt

By Atty.

UNITED STATES PATENT OFFICE.

JOSEPH PELT, OF NEWARK, NEW JERSEY.

DESIGN FOR A KNITTED CAPE.

61,276.

Specification for Design.

Patented July 25, 1922.

Application filed February 16, 1922. Serial No. 738. Term of patent 3½ years.

To all whom it may concern:

Be it known that I, JOSEPH PELT, a citizen of the United States, residing at Newark, in the county of Essex and State of New Jersey, have invented a new, original, and ornamental Design for a Knitted Cape, of which the following is a specification, reference being had to the accompanying drawing, forming part thereof.

The figure is a view of a knitted cape, showing my new design.

I claim:

The ornamental design for a knitted cape as shown.

JOSEPH PELT.
